UNITED STATES PATENT OFFICE

2,656,451

ILLUMINATED ROTARY CLOTHES-
WASHING BASKET

Hilda Rick, Manitowoc, Wis.

Application January 2, 1951, Serial No. 203,817

2 Claims. (Cl. 240—2)

1

The present invention relates to new and useful improvements in automatic clothes washers and more particularly to illuminating means for the rotary basket of the washer.

An important object of the invention is to provide means for illuminating the interior of a rotary clothes washing basket by a lamp positioned inside the washer and outside of the basket and protected from contact with water used in washing and to this end to construct the basket with an annular window in its end adjacent the clothes door and also constructing the stationary cylinder of the washer with a window between the lamp and the basket window to thus shield the lamp from water.

Another object is to provide a switch for the lamp controlled by the clothes door of the washer to energize the lamp when the door is opened and to de-energize the lamp when the door is closed.

A further object is to provide illuminating means for clothes washers which is simple and practical in construction, efficient and dependable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a vertical sectional view of the washer showing the location of the lamp therein;

Figures 2 and 3 are transverse sectional views taken on the lines 2—2 and 3—3 of Figure 1;

Figure 4 is a fragmentary front elevational view of the washer and with the clothes door broken away to show the switch;

Figure 5 is a fragmentary sectional view taken on a line 5—5 of Figure 4;

Figure 6 is an enlarged sectional view of the switch; and

Figure 7 is a diagram of the circuit for the lamp.

Referring now to the drawings in detail, wherein for the purpose of illustration I have disclosed a preferred embodiment of my invention, the numeral 5 designates a conventional type of automatic clothes washer which includes a casing 6 having a clothes door 7 at its front. The opening 8 of the stationary cylinder 9 is connected to the front opening 10 by a rubber vibration damping and sealing tube 11.

The front end of cylinder 9 is provided with

10 a glass covered window 12 above the opening 8 aligned with an annular glass covered window 13 which is positioned concentrically with the clothes opening 14 in the front end of the rotary basket 15 of the washer, which is secured to a shaft 16 journaled in the rear end of the cylinder and driven by a belt 17 from a motor 18 at the rear of the washer. The edges of the windows 12 and 13 are sealed in rubber strips 19 and 20.

15 A lamp 21 is supported by a bracket 22 in front of window 12 and is connected to a conventional type of door operated switch 23 which includes a plunger 24 sliding in the front of the casing 6 in the path of closing movement of the door 7. A coil spring 25 projects the plunger outwardly to close the switch and energize the lamp when the door is open, while the plunger is moved inwardly to open the switch and de-energize the lamp when the door is closed.

20 Accordingly, when the door 7 of the washer is closed the switch cuts off the lamp while the washer is running and when the washing operation is completed and the door 7 is opened, the lamp 21 is energized to illuminate the interior of the basket 15 so that the operator may easily see the condition of the clothes and to eliminate the possibility of leaving part of the washed clothes in the basket when removing the same.

25 In view of the foregoing description taken in conjunction with the accompanying drawings it is believed that a clear understanding of the construction, operation and advantage of the device will be quite apparent to those skilled in this art. A more detailed description is accordingly deemed unnecessary.

30 It is to be understood, however, that even through there is herein shown and described a preferred embodiment of the invention the same is susceptible to certain changes fully comprehended by the spirit of the invention as herein described and the scope of the appended claims.

35 Having described the invention, what is claimed as new is:

1. In combination, a washing machine including a casing having a clothes door in its front wall, a stationary cylinder in the casing spaced from at least one wall thereof to form a chamber between the said wall of the casing and the cylinder, and said cylinder having an axial opening in its front wall aligned with the door, a clothes loading and unloading tub leading from the door to the opening in the cylinder, a rotary tub in the cylinder also having an axial opening in its front wall aligned with the first named opening, a glass covered window in the stationary cylinder,

a glass covered window in the rotary tub registering at all times with the first named window, and a lamp in the chamber of the casing in front of the first named window to illuminate the interior of the tub through said windows. 5

2. In combination, a washing machine including a casing having a clothes door in its front wall, a stationary cylinder in the casing spaced from at least one wall thereof to form a chamber between the said wall of the casing and cylinder, and said cylinder having an axial opening in its front wall aligned with the door a clothes loading and unloading tube leading from the door to the opening in the cylinder, a rotary tub in the cylinder also having an axial opening in its front wall aligned with the first named opening, a glass covered window in the stationary cylinder, an annular glass covered window in the rotary tub concentric to the axial opening therein and register-

ing at all times with the first named window, and a lamp in the chamber of the casing in front of the first named window to illuminate the interior of the tub through said windows.

HILDA RICK.
